UNITED STATES PATENT OFFICE.

WALTER T. GODDARD, OF HAMILTON, ONTARIO, CANADA, ASSIGNOR TO LOCKE INSULATOR CORPORATION, OF BALTIMORE, MARYLAND, A CORPORATION OF MARYLAND.

INSULATOR.

Application filed January 6, 1923. Serial No. 611,132.

The invention relates to insulators, and more particularly to means for connecting the parts of an insulating member to each other, and to the method of applying said means. To this end the principal object of the invention, generally stated, consists in providing a metallic connecting member adapted to be interposed between adjacent surfaces of an insulator, said connecting member being adapted to form a rigid bond between the adjacent surfaces.

Another object of the invention consists in providing a bonding member for connecting parts of an insulator, said bonding member being unaffected by exposure to atmospheric conditions and being adapted to be inserted into and removed from between the adjacent surfaces without detriment to the latter or to the adjacent members.

Another object of the invention consists in connecting adjacent surfaces of an insulator by interposing therebetween a series of metallic units.

A still further object of the invention consists in the method of connecting adjacent surfaces of an insulator by pouring therebetween spaced bands, strips or sections of molten metal.

There are other objects of the invention, as will hereinafter be set forth in the detailed description of the insulator and the method of connecting the same, which I have illustrated in the accompanying drawing forming a part of this application.

In the drawings.—

Figure 1 is a view, partially in section and partially in side elevation, of a multiple unit insulator of the pin type, showing the invention applied thereto.

Figure 2 is a transverse horizontal sectional view taken on the line 2—2 of Fig. 1.

Figures 3 and 4 are fragmentary sectional views showing on a somewhat larger scale the method of connecting insulating units.

Figure 5 is a view, partially in vertical section and partially in side elevation, of a conventional type of suspension insulator showing the parts thereof connected by the method which I have devised.

Figure 6 is a transverse horizontal sectional view taken on the line 6—6 of Fig. 5.

Figure 7 is a top plan view of the cap illustrated in Fig. 5.

Figure 8 is a fragmentary view, partially in side elevation and partially in section, showing the invention applied to a post insulator.

Throughout the various figures like parts are designated by like reference characters.

Referring first to the construction shown in Figs. 1 to 4, inclusive, the numeral 1 designates the cap or uppermost section of a conventional pin type insulator having the usual line wire groove or recess 2, the tie wire groove 3, and being provided on its under face with a centrally disposed cavity 4. Within the cavity 4 is the cap or stem 5 of the base or co-acting unit of the insulator. It is to be understood that while I have illustrated a two unit pin type insulator, the invention is not to be construed as being limited to this only since it will be apparent from the detailed description of the invention that it is equally applicable to various other forms of insulators.

To connect the units 1 and 5, I preferably form on the connected surfaces thereof roughened or corrugated portions 6, these portions being arranged opposite each other when the insulating units are assembled. The stem 5 of the base member is of less diameter than the diameter of the recess 4 so that when the parts are assembled they will be spaced apart, as shown in the drawings. I interpose between the units a washer or spacing member 7 which is preferably formed of felt, asbestos, or like material. This spacing member overlies the head 5 of the base unit and is preferably formed with a series of notches or recesses 8 opening from the peripheral edge thereof, the peripheral edge of the spacing member 7 terminating preferably at a point within the recess 4.

When the parts are assembled as shown in Fig. 1, the insulator is inverted and a molten metallic substance 9, preferably lead or an alloy thereof, is poured within the recess 8 of the spacing member or washer 7. It will be obvious that the size and spacing of the molten alloy connecting strips is determined by the size and spacing of the notches or recesses 8 within the washer or spacing member 7 and may be arranged or altered as desired.

In Fig. 5 there is illustrated a suspension insulator comprising a metallic cap 10 hav-

ing a downwardly opening recess 11 and upwardly projecting perforated ears 12, the latter providing means for connecting the cap to an adjacent insulator or to a support, 5 as the case may be. The recess 11 is adapted to receive the neck or stem 13 formed on and projecting from the upper face of the insulating unit 14. The unit is likewise provided with a centrally arranged downward- 10 ly opening cavity or recess 15 in which is received the stem 16 of the eye-bolt 17. The inner wall of the recess 11 is preferably corrugated as shown at 18 and the vertical surface of the neck or stem 13 is roughened preferably by the so-called sanded process. This 15 process consists in applying to the neck or stem a sand formed by granulating fired porcelain which adheres to the freshly glazed surface of the stem and which is fused to 20 the stem upon the firing of the insulator.

The method of connecting the cap 10 to the stem 13 is as follows: Seated within the cap is a felt or asbestos washer or pad 19 which is preferably provided with a series of 25 spaced fingers 20 which may correspond in length with the depth of the cap. This washer is positioned within the cap so that the openings between the fingers 20 thereof are in alignment with the openings 21 provided in the upper face of the cap, as clearly shown in Fig. 7. The cap is then placed over the neck or stem until the washer 19 is in contact with the top of the stem 13 and molten metal, as hereinbefore described, 30 is then poured through the openings 21 so that the molten metal on solidifying forms a firm bond, as indicated at 9, between the cap and the stem.

A like method is employed to connect the 40 eye-bolt 17 within the recess 15. The vertical wall of the recess is provided with a roughened or sanded surface and a washer 19^a having a plurality of fingers 20^a is seated within the recess 15, preferably by assembling the washer and eye-bolt and forcing the assembled washer and eye-bolt into proper position. The spaces between the fingers 20^a are then filled with the molten metal or alloy and the latter on solidifying forms a firm 45 bond between the stem 16 of the eye-bolt and the adjacent walls of the recess 15, the corrugations 22 on the stem 16 of the eye-bolt materially improving the grip between the 50 alloy and the eye-bolt.

In Fig. 8 I have illustrated a fragmentary portion of a post or column insulator having a metallic base member 23 on the upper surface of which is provided a circular flange 24 within which is adapted to seat the base 55 25 of the post insulator 26. The latter is preferably provided with a corrugated surface, as shown at 27, to increase the leakage distance and may have the base portion 25 thereof sanded so as to form a roughened 60 surface, as hereinbefore described. To con-

nect the insulator 26 to the base member 23 I interpose between the inner wall of the flange 24 and the circumference of the base a strip or spacing member preferably composed of felt or asbestos or like material, as 70 illustrated at 28. The said strip is preferably formed with a series of spaced upstanding fingers or tongues 29 and the spaces between the said tongues 29 are then filled with a molten metal or alloy which on solidifying forms 75 a rigid bond serving to firmly connect the insulator to the base member. If desired the inner wall of the flange 24 may be corrugated or roughened as shown at 30.

Throughout all of the devices illustrated 80 the molten metal on hardening interlockingly connects the adjacent surfaces between which it is interposed against separation. The shrinkage of the metal on cooling from its molten stage provides sufficient clearance 85 between the adjacent surfaces to compensate for the thermal changes in the latter, and therefore does not subject these surfaces to excessive strains. In this connection it might be pointed out that a metal connecting member being a good conductor of heat serves to 90 equalize the temperatures of the adjacent surfaces.

Another great advantage of the method of connecting insulators as shown and described 95 herein resides in the ease by which these units may be disassembled if desired. By immersing the connected units in a bath of oil whose temperature is above the melting point of the metallic bond, or by subjecting the units to 100 this temperature, which temperature is not detrimental to the material forming the parts of the insulator, I am enabled to melt the bond and hence may disconnect the units 105 without detriment to the latter.

By spacing the parts of the connecting metal apart, that is, by utilizing a series of spaced strips, bands or segments, I am enabled to use as the connecting medium a metal or alloy whose melting point is comparatively high, such, for instance, as lead, 110 which is cheap and which, on cooling, forms a bond having the requisite tensile strength to satisfactorily perform the functions required. Another result of the spacing of 115 these units resides in the fact that no detrimental heating effects are produced even when a metal having a relatively high melting point is used as the connecting medium since by interrupting the continuity of the 120 metal by felt strips or the like the detrimental heating effects of a large body of metal at a high temperature is avoided.

Having now described the invention, what I claim and desire to secure by Letters Patent is:—

1. The method of connecting an insulating unit to an adjacent member which consists in assembling said unit and said member in nested relation with spacing means there- 130

between, and finally connecting adjacent surfaces of said unit and member at spaced intervals by pouring molten metal therebetween.

- 5 2. The method of connecting parts of a multiple unit insulator which consists in providing adjacent surfaces of said parts with roughened portions, assembling said surfaces in nested relation with a spacing device therebetween leaving spaced pockets between the parts, and finally connecting the adjacent surfaces at spaced intervals by pouring molten metal into said pockets.
- 10 10

3. The method of connecting parts of a multiple part insulator which consists in forming a cavity in one of said parts, forming a neck or stem on another of said parts, roughening portions of the surface of said cavity and said stem, assembling said parts 15 by inserting the said stem within the said cavity, spacing means being employed for dividing the cavity between the parts into a series of pockets and finally connecting the roughened portions of said adjacent surfaces 20

at spaced intervals by pouring a molten metallic alloy in said pockets.

4. The method of connecting units of a multiple part insulator which consists in forming a cavity in one of said parts and forming a stem on another of said parts, said stem and cavity being adapted to be assembled in nested relation, applying a spacing member between said units, and finally connecting adjacent portions of said surfaces by pouring therebetween a metallic alloy in 30 35

a molten state.

5. The method of uniting porcelain insulator sections comprising arranging the sections in nested relation with a circumferential space between them, obstructing the 40 spaces at intervals between the sections, and filling said spaces with molten metal, contiguous portions of the sections having roughened surfaces providing a grip for the metal.

In testimony whereof I affix my signature.

WALTER T. GODDARD.
